UNITED STATES PATENT OFFICE.

JOHN P. EUSTIS, OF NEWTONVILLE, MASSACHUSETTS.

DESIGN FOR A RECEPTACLE.

SPECIFICATION forming part of Design No. 35,676, dated February 4, 1902.

Application filed November 29, 1901. Serial No. 84,143. Term of patent 7 years.

To all whom it may concern:

Be it known that I, JOHN P. EUSTIS, a citizen of the United States, residing at Newtonville, in the county of Middlesex and State of Massachusetts, have invented and produced a certain new and original Design for a Receptacle, of which the following is a specification, reference being had therein to the accompanying drawings.

Figure 1 is a plan view of a receptacle, showing my new design. Fig. 2 is a side elevation of the same.

As shown in the drawings, the leading or material feature of my design consists of a cylindrical margin A, which forms the upper portion of the receptacle, and the cross-sectionally concavo-convex enlargement B,

which forms the lower part of the side walls of the receptacle. Said enlargement B is intermediate the marginal portion A and the bottom a of the receptacle. The upper edge of the marginal portion A is formed with ball-like ornamentation b, as shown.

Having described my invention, what I claim as new, and desire to secure by Letters Patent, is—

The design for a receptacle, as herein shown and described.

In testimony whereof I affix my signature in presence of two witnesses.

JOHN P. EUSTIS.

Witnesses:

M. E. COVENEY,
E. A. ALLEN.
